W. G. MacLEAN, JR

ANIMAL MOUTH TONGS

Filed March 5, 1928

Wm. George MacLEAN JR.,
INVENTOR.

BY *Harold C. Shipman*
ATTORNEY

UNITED STATES PATENT OFFICE.

WILLIAM GEORGE MACLEAN, JR., OF ARNPRIOR, ONTARIO, CANADA.

ANIMAL-MOUTH TONGS.

Application filed March 5, 1928, Serial No. 259,286, and in Canada February 13, 1928.

This invention relates to animal mouth tongs and has for its particular object a means for independently engaging the upper and lower jaws of an animal.

5 A further object is to provide a means whereby the clamp portions can be operated independently of the bit portions.

10 A further object is to provide a means whereby the upper bit and clamp portions may be moved relative to the lower bit and clamp portions.

15 With the foregoing and other objects in view, as will appear as the description proceeds, the invention consists of the novel construction, combination and arrangement of co-operating elements as hereinafter more specifically set forth, claimed and shown in the accompanying drawings forming a part of the present application, in which:

20 Fig. 1 is a side plan view, showing the parts in position ready for the animal to engage the bit portions.

25 Fig. 2 is a side plan view, showing the clamp portions moved into engageable position relative to the bit portions.

Fig. 3 is a side plan view, showing the parts in position as if holding apart the jaws of the animal.

30 Fig. 4 is an end view, parts being in the position similar to that shown in Fig. 1.

Like numerals of reference designate corresponding parts throughout the different views.

35 5 and 6 indicate co-operating handles, having inwardly directed portions 7 and 8 respectively, which portions are fulcrumed together as at 9. The inner ends of the handles converge, as at 10 and 11, and are provided with bit portions 12 and 14 respectively at 40 their outer extremities. The bit portions 12 and 14 have flared tines extending downwardly and upwardly respectively. These tines guide the animal's jaws towards the central cross portion of the bit portions. The central cross portion of the bit portions 12 and 14 45 may be wound with tape or covered in any other suitable manner to prevent a direct contact of the animal's teeth on the metal forming the bit portions.

50 Pivotedly mounted in connection with the handle 6, I provide an upper clamp 15 and pivotedly mounted in connection with the handle 5, I provide a lower clamp 16. The outer or free end of each of the clamps 15 and 55 16 is provided with a U-shaped clamping jaw

17 and 18 respectively. These jaws are carried on the clamps 15 and 16 in such a manner that when closed to engaged position, as shown in Figs. 2 and 3, they are outwardly of the bit portions 12 and 14 and the clamp 60 15 may extend between the flared portions of the bit 14, while the clamp 16 may extend between the flared portions of the bit 12, so that in this way, my device will provide for the engagement of the jaws of various size animals between the bit portions 12 and 14 and their respective clamping jaws 18 and 17.

The inner end of the clamp 16 is provided with an arcuate slot 19. The inner end of the clamp 15 is provided with an annular 70 opening adapted to register with the arcuate slot 19. 20 is a lever hingedly mounted to the handle 6 and provided with side connecting links 21. The lower end of the links 21 are provided with annular openings and a pin 75 25 extends therethrough, engaging through the annular opening in the inner end of the clamp 15 and through the arcuate slot 19. 22 is a catch member having one end suitably tensioned by the coil spring 23 for engagement in the ratchet face 24 formed on the upper face of the handle 6. When it is desired to clamp the jaws of an animal, such as a fox, the operative end of the mouth tongs is extended into the animal cage with the bit 80 85 portions 12 and 14 directed as close as possible to the mouth of the animal. Under such circumstances, the common tendency of the animal is to snap at the bit portions 12 and 14, with the result that the animal's fangs 90 engage over the bit portions 12 and 14. Immediately the animal takes at the bit portions 12 and 14, the person using the device presses the free end of the lever 20 towards the handle 6 which will change the position of the operative parts from that shown in Fig. 1 to that shown in Fig. 2, the clamping jaw 17 now being engaged over the nose portion of the animal, while the clamping jaw 18 is engaged under the lower jaw of the animal. 100 As the free end of the lever 20 is moved towards the handle 6, the engagement end of the catch member 22 is drawn over the ratchet face 24 and in co-operation with the link members 21, retain the jaws 17 and 18 in their closed positions as shown in Figs. 2 and 3.

If it is desired to look into the animal's mouth or to administer medicine to the animal, the outer ends of the handles 5 and 6 may be pressed together, which action will space 110

apart the converged ends 10 and 11, carrying with them the clamps 16 and 15 respectively. The connecting pin 25 carried by the lower ends of the links 21 will be permitted to move in the arcuate slot 19.

- 5 After the animal has been examined or medicine administered, the thumb portion 26 of the catch member 22 will be pressed towards the lever 20, thus disengaging its opposite end from the ratchet face 24 and permitting the lever 20 to now return to its position as shown in Fig. 1, which will again space apart the clamping jaws 17 and 18, thus permitting release of the animal.
- 10 15 The foregoing specification and annexed drawings disclose the preferred embodiment of my invention, but it is to be understood that minor changes may be resorted to in the commercial adaptation of my invention
- 20 25 without departing from the scope of the invention as hereinafter claimed.

What I claim as new is:

1. Animal mouth tongs comprising a pair of co-operating handles fulcrumed together; 25 the forward ends of said handles converging and each provided at its outer extremity with a bit; a clamping member pivotally carried by each forward end and each provided at its outer extremity with a clamping jaw and 30 a lever for operating said clamping members.
2. Animal mouth tongs comprising a pair of handles; bit portions adapted to be spaced apart by said handles; clamping jaws co-operating with said portions for engagement 35 of the upper and lower jaws of an animal.
3. Animal mouth tongs comprising suitably mounted bit portions and clamping jaws movable jointly with said bit portions.
4. Animal mouth tongs comprising suit- 40 ably mounted bit portions; clamping jaws movable jointly with said bit portions; a means of adjusting said jaws relative to said bit portions and a means of retaining said jaws in adjusted position.
- 45 5. Animal mouth tongs comprising suitably mounted bit portions; clamping jaws adapted to co-operate with said bit portions;

a means of adjusting said jaws relative to said bit portions and a means of spacing apart said bit portions when said jaws are in adjusted position.

6. Animal mouth tongs comprising a pair of pivotally connected handles; an integral bit portion carried by the forward end of each of said handles and a means for retaining the animal's jaws in contact position relative to said bit portions.

7. Animal mouth tongs comprising a pair of pivotally connected handles; an integral bit portion carried by the forward end of each of said handles and an adjustable means carried adjacent the forward end of each of said handles for co-operatively retaining the animal's jaws in contact position relative to their respective bit portions.

8. Animal mouth tongs comprising a pair of pivotally connected handles; bit portions carried at one end of each of said handles; an adjustable clamping jaw member carried by each of said handles and a means for simultaneously adjusting said members relative to said portions.

9. Animal mouth tongs comprising bit portions adapted to be moved apart; co-operating clamping jaws movable with said portions but adjustable relative thereto and means for adjusting said jaws.

10. Animal mouth tongs comprising a pair of pivotally connected handles; bit portions carried at one end of said handles; a clamping jaw member pivotally connected to one of said handles to co-operate with the bit portion carried by said handle and a means for adjusting said member relative to said portion.

11. Animal mouth tongs comprising bit portions adapted to be moved apart simultaneously and a co-operating clamping jaw member for each of said portions, adapted to be adjusted simultaneously relative to their respective portions.

In testimony whereof, I affix my signature.

WILLIAM GEORGE MACLEAN, JR.
